United States Patent Office

Des. 208,951
Patented Oct. 17, 1967

208,951

JUG

Leo Sorenson, Manitowoc, Wis., assignor to Northern Laboratories, Manitowoc, Wis., a corporation of Wisconsin

Filed July 1, 1966, Ser. No. 2,901

Term of patent 14 years

(Cl. D58—5)

Fig. 1

Fig. 2

Fig. 4

FIG. 1 is a front perspective view of a jug, embodying my new design;

FIG. 2 is a rear perspective view;

FIG. 3 is a top plan view; and

FIG. 4 is a side elevational view thereof.

I claim:

The ornamental design for a jug, as shown.
